(57) **CLAIM**

The ornamental design for a hammer stapler grip, as shown and described.

DESCRIPTION

FIG. 1 is a front perspective view of a hammer stapler grip depicted as installed on a hammer-type stapler, showing my new design;

FIG. 2 is a front perspective view of the hammer stapler grip; FIG. 3 is a front view thereof with a rear view being a mirror image;

FIG. 4 is a left side view thereof with a right side being a mirror image;

FIG. 5 is a top view thereof; and,

FIG. 6 is a bottom view thereof.

The broken lines shown in the drawings represent unclaimed portions of the hammer stapler grip and form no part of the claimed design.
